UNITED STATES PATENT OFFICE

2,619,091

CIGARETTE HOLDER WITH SCOOP FOR FILTER MATERIAL

Irving Florman, New York, N. Y.

Application April 20, 1950, Serial No. 157,013

1 Claim. (Cl. 131—207)

1

This invention relates to cigarette and cigar holders.

It is an object of the present invention to provide means facilitating collection and insertion of filtering material in parts of a cigarette holder whereby to avoid capsules and other compressed filtering assemblies heretofore used in such holders.

Still another object of the invention is to provide means offering the possibility of controlling the quantity of the filtering material to be used or the necessity for change and removal thereof.

Other objects of the present invention are to provide means affording ready filling of the cigarette holder with loose, granular filtering material, ensuring simple construction and inexpensive manufacture of the holder which has a minimum number of parts, is compact, has easily separable parts to effect the filling of the same with filtering material, and is efficient in operation.

For other objects and for a better understanding of the invention, reference may be had to the following detailed description taken in connection with the accompanying drawing, in which

Fig. 1 is an elevational view of the holder with portions thereof broken away and shown in section whereby to display the interior construction of the holder.

Fig. 2 is a fragmentary perspective view looking upon the part containing the scoop which receives and gathers the filtering material.

Fig. 3 is a perspective view showing the mouth piece part being extended into a box of the filtering material to scoop a quantity of the same.

Referring now to the drawing, 10 represents a mouth piece having a bore 11 extending therethrough. Said bore provides a smoke passage extending from a large recess 12 in the outer end of the mouth piece 10. In this recess and extending outwardly therefrom is an externally threaded coupling member 13 having threaded engagement with the outer end of the mouth piece and is adapted to receive a housing part 14 having a tubular section.

Within the recess 13 is a sleeve or scoop member 15 adapted to receive and retain filtering material 16, such as silica gel, clay and other granulated material. This sleeve 15 has a scoop section 17 terminating in an inclined open end edge. With the mouth piece 10 removed from the housing member 14, the mouth piece can be used as a handle for the scoop portion 17 adapted to enter a relatively flat box 18 in such a manner as to gather the filtering material 16 therefrom and to

2

observe the collected filter material in the scoop section. With the sleeve or scoop 15 filled with the material, the mouth piece 10 can be further connected to the housing member 14 and receptor 23 by threaded portions at 13.

When the inclined open end edge of section 17 is inserted in hollow housing or section 14 the filtering material 16 then fills out said latter section 14 and is in contact with a substantial portion of the inner wall surface thereof, as seen in Fig. 1.

Fixed to the housing member 14 is a hollow spindle 21 having a passage or bore 22 extending therethrough and communicating with the filtering material. Adjustable on this spindle is the receptor or end member 23 that has a skirt portion 24 slidable upon the part 14. The spindle shaft is flared at its outer end, as indicated at 26, to prevent the outward displacement of the member 23. A spring 25 is disposed about the spindle shaft and reacts between the member 23 and the end wall defining the housing part 14 to hold the member 23 in its extended position. When it is desired to remove a cigarette from the holder, the member 23 is adjusted on the spindle shaft so that the flared end 26 will eject the cigarette from retaining opening 27 in the member 23. The housing part 14, the spindle shaft 21, the ejecting member 26 and the spring 25 provide a unitary assembly which is separable from the mouth piece 10 that contains the scoop 15.

The scoop 15 may be provided with slots or long apertures which may serve as windows to see when the filtering material needs to be changed. The housing part 14 surrounding the scoop is of transparent material so that observation can be made through such windows. Such an opening or slot is indicated at 28 and the same is of smaller diameter than the average diameter of the respective particles of the filtering material.

The sleeve or scoop 15 is formed of a hollow cylindrical tubing section by cutting the same on a bias to obtain said inclined end edge 17. The scoop fits the recess 12 in a sufficiently tight manner so that it will not leave the mouth piece 10 when it is used. As apparent from Fig. 1 scoop section 15 in recess 12 and housing section 14 define a chamber for accommodating said filter material 16 in a relatively compact condition, said scoop section and said housing section frictionally engaging each other to thereby detachably couple the mouthpiece 10 to receptor 23.

While various changes may be made in the detail construction, it shall be understood that such changes shall be within the spirit and scope

of the present invention as defined by the appended claim.

Having thus described the invention, what is claimed as new and desired to be secured by Letters Patent, is:

A smoker's article comprising a mouthpiece portion, a socket portion adapted to receive a cigarette, and a filter chamber therebetween having end walls with bores of smaller diameters than the diameter of said chamber, said mouthpiece portion being separable from said socket portion, such separation being effective at said chamber, said chamber being defined by a pair of concentric and telescoping tubes, one of said tubes being attached to one of said portions and terminating in an inclined edge whereby said one tube by means of its inclined edge may be used as a scoop container and with said one portion as a handle for said scoop container to facilitate scooping and retaining of comminuted filtering means therein, the other tube being engageable with said one tube to support said one portion and said scoop container within said other tube, whereby to connect said socket portion to said mouthpiece portion through said chamber, and 25

fastening means located at one end of said inclined edge for joining said mouthpiece portion to said socket portion and for locating the other end of said inclined edge at one of the end walls of said chamber.
